UNITED STATES PATENT OFFICE.

FLORENCE GENEVIEVE RYAN, OF CHICAGO, ILLINOIS.

LAUNDRY CART.

Application filed September 28, 1923. Serial No. 665,496.

To all whom it may concern:

Be it known that I, FLORENCE G. RYAN, a citizen of the United States, residing at Chicago, in the county of Cook and State of Illinois, have invented new and useful Improvements in Laundry Carts, of which the following is a specification.

This invention relates to a laundry cart and has for its primary object the construction of a cart by means of which clothes may be sorted and besides the operator relieved of strain in conveying the clothes from one place to another.

An object of the invention is the novel manner of constructing bags and arranging the same in various positions with and combining the basket support so that a basket of clothes may be readily conveyed to a place to be dried, and the dried pieces sorted in various bags.

Besides the above my invention is distinguished in a laundry cart that can be folded into a compact space.

With these and other objects in view the invention may be better understood from the following detailed description taken in connection with the accompanying drawing wherein:

Fig. 1 is a side elevation of the cart.

Fig. 2 is a top plan view.

Fig. 3 is an end elevation.

Fig. 4 is a sectional view on the line 4—4 of Fig. 1.

Fig. 5 is an enlarged end elevation of the side frames.

Fig. 6 is a sectional view on the line 6—6 of Fig. 2.

Again referring to the drawings illustrating one of the many constructions of my invention the numerals 1 and 2 designate a pair of side frames including the top bars 3 and wheels 4. The top bars 3 are connected together by a flexible support 5 which in this particular instance is made of canvas so that clothes may be arranged directly on the support or clothes basket arranged on the support. The bars 3 have their ends formed into handles 6 and removably engaging the handles are the loops 7 of the clothes pin receiving bags 8 that are provided with drawstrings 9. The side frames are held in extended upright position relative to each other by the pivoted links 10 and the lock bar 11 that is pivotally connected to one side frame as indicated at 12 and has de-

tachable engagement with the pin 13 secured to the other side frame. Side bags 14 are removably connected to hooks 15 projecting from the top bars 3 and are further braced by the flexible members 16. End bags 17 are supported at the ends of the side bags for receiving small articles.

From the foregoing description taken in connection with the accompanying drawings it will be seen that I provide a simple substantial construction which will allow clothes to be conveyed from place to place with very little effort and at the same time allow proper sorting thereof.

It is of course, to be understood that the various bags may be constructed in other ways and connected to the frames in other manners and besides the side frames may be constructed in other ways and have other collapsible engagement with each other, therefore I do not desire to be limited in any manner except as set forth in the claims hereunto appended.

Having thus described my invention what I claim is:

1. A collapsible laundry cart comprising side frames, top bars extending longitudinally of the frames, a flexible support spanning the distance between the top bars and having its edges connected thereto, means pivotally connecting the side frames at their ends to permit folding movement toward each other, lock bars at the ends of the frames, each having one end connected to one side frame and the other end detachably connected to the opposite side frame and side bags removably supported along the sides of the top bars.

2. A collapsible laundry cart including normally spaced side frames, top bars along the upper edges of said frames, a flexible support having its edges connected to the top bars, pivoted links at the ends of the frames whereby to connect said frames for folding movement, lock bars at the ends of the frames each having one end pivotally connected to one of said frames and the other end detachably connected to the opposite frame, hook members carried by the top bars and extending laterally from said bars and receiving bags removably mounted upon said hooks.

In testimony whereof I affix my signature.

FLORENCE GENEVIEVE RYAN.
